UNITED STATES PATENT OFFICE.

CASPER ENGH, OF LIEGE, BELGIUM, ASSIGNOR TO LA MANUFACTURE
LIEGEOISE D'ARMES À FEU SOCIÉTÉ ANONYME, OF SAME PLACE.

MAGAZINE-GUN.

SPECIFICATION forming part of Letters Patent No. 430,936, dated June 24, 1890.

Application filed April 24, 1889. Serial No. 308,347. (No model.)

To all whom it may concern:

Be it known that I, CASPER ENGH, a subject of His Majesty the King of Norway and Sweden, residing at Liege, Belgium, have invented certain new and useful Improvements 5 in Magazine-Guns, of which the following is a specification.

My invention relates to improvements in magazine or repeating guns and belongs to 10 the class of bolt-guns, the bolt moving rectilinearly in the direction of the axis of the barrel, the magazine being placed in the center of the arm in front of the trigger-guard. The closing of the breech is axial, and is effected in a plane perpendicular to that of the 15 axis of the barrel. The locking is by two lateral projections symmetrically placed upon the working-handle. These projections find abutments in two corresponding mortises 20 within the walls of the body. These abutments are diametrically opposite and situate in a plane at right angles to that of the axis of the barrel. At the intersection of the 25 planes the reaction of the charge is concentrated.

To facilitate the description of the general movements of the mechanism and the functions of each of the pieces constituting the moving breech and the magazine, it is necessary 30 to examine separately each of the parts which together perform successively the movements for opening and closing the breech for the percussion, for the extraction, and for the ejection of the empty case and those of the apparatus and the magazine for 35 repetition.

In the accompanying drawings, Figure 1 is an elevation of a part of the gun after firing. Fig. 2 is a plan view of same after firing. 40 Fig. 3 is a longitudinal section of the breech mechanism along the axis of the barrel, the bolt being represented in its midway position, the breech being partially open. Fig. 3^a, Sheet 5, is a similar view with the bolt partly 45 in side elevation, showing the action of the stop-piece for limiting the rearward movement of the bolt to adapt the arm to "shot-by-shot" firing. Fig. 3^b is a similar view showing the action of the stop-piece for magazine

firing. Fig. 3^c is a sectional view with the bolt in its forward position, showing the action of the safety-bolt for holding the striker against action. Fig. 4 is an external view of the breech-box. Fig. 5 is a plan of the top of the box. Fig. 6 is a longitudinal section of 55 the breech-box along the axis of the barrel. Fig. 7 is a view of the under side of the breech-box. Fig. 8 is a horizontal section of the breech-box along the axis of the barrel or on the line *v v*, Fig. 6. Fig. 9 is a transverse section of 60 the breech-box on lines *x x*, Figs. 6 and 8. Fig. 10 is a transverse section of the breech-box on lines *z z*, Figs. 6 and 8. Fig. 11 is an external view of the bolt. Fig. 12 is a longitudinal section of the bolt along the axis of the barrel. 65 Fig. 13 is an under side view of the bolt. Fig. 14 is a transverse section of the bolt on line *y y*, Fig. 11. Fig. 15 is a transverse section of the bolt on line *w w*, Fig. 11. Fig. 16 is an end elevation of the bolt. Fig. 17 is a side 70 elevation of the striker. Fig. 18 is a top view of same. Fig. 19 shows plan and side views of the link. Fig. 20 shows the right side of the working-handle. Fig. 21 shows the left side of same. Fig. 22 is a back view of same. 75 Fig. 23 is a section of the working-handle along the axis of the barrel or on the line *v v* of Fig. 22. Fig. 24 shows an elevation and plan of the mainspring. Fig. 25 shows an elevation and plan of the sear. Fig. 26 shows 80 an elevation and plan of the safety-bolt. Figs. 27 and 28 show an elevation, plan, and end view of the extractor. Fig. 29 is a view of the right side of the magazine together with the trigger-guard. Fig. 30 is a plan of 85 the same piece. Fig. 31 is a view of the left side of the magazine. Fig. 32 is a plan of this piece. Fig. 33 is an elevation and plan of the lever which raises the cartridges. Fig. 34 is an elevation and plan of the spring of 90 the elevating-lever. Fig. 35 is an elevation, back view, and plan of the stop-lever of the cartridge-box. Fig. 36 is an elevation and plan of the spring of the stop-lever; Fig. 37, an elevation and plan of the trigger; Fig. 38, 95 an elevation and plan of the bolt-stop; Fig. 39, an elevation, plan, and under side view of the turn-button which actuates the bolt-stop;

Fig. 40, an elevation and plan of the link connected with the bolt-stop; Fig. 41, side, front, and back views of the cartridge-box.

The mechanism for opening and shutting 5 off the breech is as follows:

The breech-box, Figs. 4, 5, 6, 7, 8, 9, and 10, is a solid piece, which is screwed onto the barrel by the screwed socket A. It is traversed longitudinally by the passage for the 10 bolt which works in grooves *a a*, cut within the walls of the same, in which also two semi-circular mortises *b*, Fig. 6, are formed on opposite sides. These are intended to receive lateral projections on the working-handle, 15 Figs. 20, 21, and 22, and thus serve for securing the breech.

At the top of the breech-box there is an opening B, to let out the empty cases and for the insertion of the box containing five cartridges. Behind the opening mentioned above is the bridge-piece C, which connects the two sides of the breech-box. Behind this the upper part of the box is open for the passage of the body of the bolt. In the upper side of 20 the right face of the box will be seen a notch D, Figs. 4 and 5, into which the arm of the working-handle E, Figs. 20, 21, and 22, enters when the breech is closed. The breech-box terminates in the rear in a tail-piece F, pierced 25 with a hole *d* to receive the tail-screw *e* of the breech-box, which traverses the grip portion of the stock and screws into the tail-piece of the trigger-guard G, Figs. 3, 29, and 30.

35 In front of the hole *d* for the tail-screw *e* of the breech-box are two grooves H to receive the bolt-stop I, Figs. 3^a, 3^b, and 38, against which the projections *f f* on the under side of the bolt, Figs. 3, 3^a, 3^b, 11, and 12, strike in 40 the backward movement of the bolt either when firing shot by shot or when firing from the magazine. The stop I also allows the bolt to come out of the breech-box when required for cleaning. These grooves H are 45 formed by leaving a projection H', which is embraced by the bolt-stop I, the latter seating in a groove *i* in same. Said stop allows also of the changing of the working of the arm from firing from the magazine to firing

50 shot by shot. It is operated by a turn-button J, Fig. 39, which is furnished on its under side with a stud or projection *g*, placed out of the center. This stud *g* engages with an oval hole *h* in a flat link-piece K, Figs. 3 and 40, 55 so that the turning of the button will advance or recede the link in its seat, which is a slot H², Fig. 6, in the breech-box. This link-piece is formed in the shape of a T, and its two branches *h' h'* engage in recesses *i* in the 60 stop I, Fig. 38. This stop is pivoted in the sides of the breech-box by its short trunnions *i'*, and is also held by its part *i*', which seats in the groove *i* of the projection H'. By the 65 action of the link K through the turn-button it is compelled to rise and fall (according as the link advances or recedes) upon the inclined plane which the under part of the two

sides of this piece presents. When the bolt-stop is raised at the forward end, the gun is arranged for intermittent firing. This action 70 is shown in Fig. 3^a, the rear movement of the bolt being limited by its projection *f* abutting against the forward end of the stop. In this position the forward end of the bolt and extractor lie over the cartridges in the magazine and keep them down; but the breech is sufficiently open to allow the insertion of cartridges for shot-by-shot action. When the stop is raised at the back, the gun is arranged for firing from the magazine, as in 80 Fig. 3^b; the magazine now being uncovered. When it is at the dead-point, it gives free passage to the bolt, which comes out of the breech-box in taking the mechanism apart. If the bolt-stop is placed in such a way that 85 the gun is arranged to fire from the magazine, all the cartridges from the magazine are used up without interruption; but by arranging the gun for intermittent firing four cartridges can be left in reserve in the magazine and 90 firing shot by shot can be carried on by inserting a cartridge each time into the bolt-channel.

In the lower part of the breech-box will be seen grooves L, Fig. 6, in the sides, into which 95 the sides L' of the magazine, Figs. 29, 30, 31, and 32, are inserted. There will be seen a cross-piece M, Figs. 3, 5, 6, 7, and 8, carrying a projection *l*, which the part *l'* of the extractor M', Fig. 27, strikes in the backward 100 movement of the bolt to eject the empty case. Near the two ends of this cross-piece M are the two tenons N N, cut out of the metal of the sides of the box, and against these the two parts m of the working-handle, Figs. 20 105 and 21, rest in the last period of the circular movement of the handle, giving a leverage, the effect of which is to force out the cartridge-case for a distance of about three millimeters to facilitate the extraction. The breech-box 110 is also cut away just below the screwed socket A at the points O O, Figs. 6, 7, and 8, so as to form hooked jaws, which engage with the attachment-hooks O' of the side pieces, of 115 which the magazine is formed, Figs. 3, 29, 30, 31, and 32.

The movable bolt P, Figs. 3, 11, 12, 13, 14, 15, and 16, contains all the mechanism for the percussion, for the extraction, and for the ejection 120 of the cartridge-cases. It effects the opening and closing of the breech, and it introduces the cartridges into the chamber. The stem of the bolt has projecting from it on the under side two longitudinal ribs *n*, which have between them a groove, in which the extractor 125 M', Fig. 27, is lodged. A circular opening P' is formed transversely in the body of the bolt. This opening is intended to receive the circular portion or axis P² of the working-handle E. Under the action of the handle the axis 130 P', and this movement causes those of the striker, of the spring and of the extractor also, as will be described farther on. At the same

time it locks the bolt against the breech of the barrel. Two semicircular slots or openings n' n^2 , adjacent to each other, are formed in each side of the lower part of the body of the bolt. 5 They are intended to receive the trunnions n^4 of the safety-bolt and the trunnions n^3 n^3 of the sear, respectively. (Shown in Figs. 26 and 25.) The breech-bolt is traversed by a passage for the striker P^3 , Figs. 17 and 18, and its rear 10 end or body portion is hollowed out to receive the mainspring, the sear, the safety-bolt, the rear end of the striker carrying the heel-piece P^4 , and the link P^5 , Figs. 3 and 19. Within the body of the bolt will be seen 15 opposite grooves Q Q , intended for receiving the two parts or limbs Q' Q' of the safety-bolt, Fig. 26, and two other opposite grooves Q^2 Q^2 , Figs. 12 and 14, in which slide the tenons p p p p of the striker, Figs. 3, 17, and 20, 18, to guide the latter. The holes r r , formed in the ribs n n on the under side of the stem of the bolt, are intended to receive a screw or pin serving as the axis for the extractor M' , and which passes through the hole r' of same. 25 Above and to one side of the circular opening P' there is on the right hand upon the outside of the body of the bolt a recess s , Fig. 11, to receive the arm of the working-handle E and to limit the course of the same. 30 The body or rear end of the bolt has parallel faces, with the exception of the upper face, which is slightly rounded on the angles and toward the back, while the stem or forward part has the form of a tube, of which the 35 under part is furnished with two ribs n n to strengthen this part of the bolt and to provide a lodging for the extractor, as herein-before described.

The striker P^3 , Figs. 17 and 18, consists 40 of a stem carrying at its hinder end a heel-piece P^4 , the sides of which are each furnished with a tenon t , which enters the slots t' t' in the limbs Q' Q' of the safety-bolt, Fig. 26, to prevent the working of the striker when 45 the finger part of the safety-bolt has been pressed down so as to come in contact with the bottom of the breech-box. In front of the heel P^4 of the striker is formed a hole t^2 , in which engages the part t^3 of the link P^5 , 50 Fig. 19. In front of the hole t^2 the body of the striker is cut to an incline to engage with the recess t^4 , formed in the circumference of the axis of the working-handle E , Figs. 3, 22, and 23. The said handle in describing its 55 backward circular movement presses upon the incline on the striker and compels it to retire and to compress the mainspring, as will be afterward described. The striker is reduced in size at the part P^6 to pass into the 60 opening t^5 of the working-handle, Fig. 22. It is prolonged to a point and has two cylindrical enlargements P^7 P^7 to guide it in the passage within the bolt. At the base of the heel P^4 of the striker is a notch t^6 , which receives 65 the nose t^7 of the sear, Figs. 3 and 25, when the mainspring R is compressed, as shown in the former figure. The link P^5 terminates in

a knuckle u , which engages with the hook a' of the upper branch of the mainspring R , Fig. 24, as shown in Fig. 3.

The sear, Fig. 25, carries near the middle the two trunnions n^3 n^3 , upon which it pivots in the holes n^2 n^2 in the sides of the bolt. It also has at one of its extremities a nose t^7 , which enters into the notch t^6 of the heel of the striker when the spring is compressed, as before described. The other extremity a^5 of the sear is rounded, and it is upon this part that the trigger acts to turn the sear, and thus disengage the nose t^7 from the notch t^6 of the 70 striker to set the latter free and allow it to advance under the influence of the mainspring communicated to it through the link P^5 .

The mainspring R , Fig. 24, has two branches. On the upper one, and near to the knuckle of the same, is a rounded projection a^2 , upon which acts the tooth a^3 , formed in the body or axis of the handle, Fig. 23, to cause the bending of the spring. The sides of the knuckle of the spring are spread out or project to facilitate the play of the two branches and to prevent them rubbing against the interior walls of the bolt in which the spring is lodged. The lower branch a^4 is rounded at its extremity and presses upon the end a^5 of the 90 sear, as shown in Fig. 3.

The hand-lever E is a very important piece of the mechanism. It is this which originates all the movements of the movable breech. It has a circular movement imparted to it upon 100 its axis, which movement extends for about one-eighth of a revolution. It is by this circular movement of the handle that the closing of the breech is effected by pressing the bolt against the base of the cartridge and the 105 rear face of the breech.

The handle is furnished with two lateral projections b^2 , Figs. 20, 21, and 22, cut in segments about one-third of the circle. By the movement of one-eighth of a revolution of the 110 axis of the handle the segments are caused to enter into the semicircular mortises b , cut in the inner walls of the breech-box, Fig. 6, against which they abut. The supporting-surfaces of the two segments are about sixty- 115 three millimeters square, which is made up as follows: width, 3.5 millimeters; length, nine millimeters—say 31.5 for each segment and sixty-three millimeters for the two.

The circular movement of the working-handle E causes the retreat of the bolt, so as first to disengage the cartridge-case from the walls of the chamber, against which it has been strongly pressed by the explosion of the charge. The case is thus forced back for a 125 distance of about three millimeters, and this considerably facilitates the extraction. It is the convex surfaces of the two segments of the axis at the point m , Figs. 20 and 21, which, by pressing upon the two lateral tenons N , 130 Figs. 6, 7, and 8, give the leverage which results in forcing back the bolt, and consequently in the disengagement of the cartridge, as has been described above. The grip and

the arm of the handle E are inclined to the right and also rearward to obtain a clear view of the sights on the barrel and to facilitate the forward and back movement for closing and opening the breech.

The safety-bolt, Fig. 26, is provided on the under side or below the finger-piece 2, where the two branches unite, with a projection b^3 , which enters into the recess at the bottom of the breech-box at the point b^4 , Figs. 5, 6, 7, and 8, to prevent the displacement of the striker if gas should enter the interior of the bolt. This is effected in the following manner: The heel P of the striker finds a solid support against the back of the finger-piece 2, and when the striker is violently forced back, in consequence of the escape of gas, the projection b^3 of the finger-piece descends automatically into the bottom of the breech-box, and this locks the safety-bolt fast.

The manner of arranging the safety-bolt is shown in Figs. 3^a and 3^b, and its position while holding the striker in Fig. 3^c.

The extractor M', Fig. 27, is a solid rod of tempered steel, pivoted as before described. At its front end it is furnished with a hook 3, which passes under the flange of the base of the cartridge and serves to withdraw the empty cartridge-case out of the chamber.

Its hinder end rests at the point 4, Figs. 3, 11, and 12, against the body of the bolt. The repeating portion of the arm is fitted to the under side of the breech-box, which receives the two sides of the magazine corresponding in form to the interior of the box. It is composed of the following parts:

First: The right side, Figs. 29 and 30, forming a single piece with the trigger-guard.

Second: The left side, Figs. 31 and 32. The two sides are connected by the aid of four dowel-pins 5, 6, 7, and 8, fixed on the right side.

Third: The cartridge-elevating lever 9, Fig. 33. This lever has at its hinder end a socket 10, having a hole which the dowel-pin 5 enters, and on this the lever works. Near the center of the elevating-lever, which forms an inclined plane, there are two lateral branches 11, 11, between which the rounded end of the bullet enters for a short distance, in order that the lever may guide the lowest cartridge in the cartridge-box to the entrance into the chamber, and at the same time may give passage to the hook of the extractor M'. The elevating-lever terminates in a rounded finger 12, which enters the cartridge-box and raises the cartridges.

Fourth: The spring 13 of the elevating-lever, Fig. 34, which has two branches. The knuckle of the spring enters a semicircular recess 14, provided in the sides of the magazine where the spring is held, Figs. 29 and 31. The rounded extremity 15 of the upper branch of the spring engages with a rounded recess 16 underneath the socket 10 of the elevating-lever 9.

The stop-lever of the cartridge-box, Fig. 35,

consists of a bent lever 20 let into the wall of the magazine and pivoting upon the dowel-pin 7. The head of this lever 20 is formed into a claw 18, 18, which enters and remains above the two sides of the cartridge-box, and in part above the base of the upper cartridge. It is held in place by the constant pressure of the two branch springs 19, Fig. 20, one branch of which abuts against the wall of the magazine and the other against the tail of the lever 20. This tail terminates in a roughened finger-piece 21, which projects within the trigger-guard. On pressing with the finger against this finger-piece the lever compresses the spring 19, and the long arm of the lever, with its claw 18, 18, is drawn back; so as to free the sides of the cartridge-box and the top of the base of the cartridge. Then the cartridge-box with the cartridges can escape from the magazine by the opening at the top of the breech-box under the influence of the magazine-elevator 9; but if no pressure be exerted upon the finger-piece the claws of the lever rest in their normal position and retain the cartridge-box and the cartridges in the interior of the magazine until the movements of the bolt oblige them to present themselves in succession in the channel of the breech-box facing the chamber of the barrel.

The trigger 22, Fig. 37, is mounted upon the dowel-pin 6, Fig. 29. It has no spring, and receives the pressure of the finger directly to cause the shot to be fired, and transmits it without any intermediate part to the rounded extremity a' of the sear.

The inner faces of the two sides of the magazine are arranged conformably to the shape of the cartridge-box which they contain.

The cartridges and the cartridge-box when in place are moved solely by the upward movement imparted to them by the elevating-lever 9. Thus it is not possible for the cartridges to move in any other way, and they cannot pass back into the interior of the magazine.

The cartridge-box 23, Fig. 41, is similar to that of the Mannlicher gun, except that it has no stop-hook at the hinder part. As soon as the magazine is empty the box is allowed to fall by its own weight, and comes out of the magazine by the opening which is made in front of the trigger-guard and at the bottom of the magazine, the elevating-lever 9 then forming a support for the cartridges when firing shot by shot.

It should be remarked that the parts of the bolt can be put together and taken apart by hand without the use of any tool, and that this mechanism does not contain any coiled spring.

The movements of the parts of the breech mechanism and the repeating apparatus are as follows: The mechanism of the gun being open, a cartridge-box containing five cartridges is introduced into the opening at the top of the breech-box, and it is pushed down

into the magazine until the claw 18 of the stop-lever catches upon the top of the cartridge-box. By this means the elevating-lever 9 is forced down and its spring 13 is compressed. The base of the upper cartridge in the box is then in front of the hook 3 of the extractor M' and of the front face of the bolt. On pushing this forward the cartridge is thrust out of the box and introduced into the chamber. The gun is then ready for firing. After the firing of the charge the working-handle E is seized with the right hand and drawn back by a direct pull. The handle then makes a circular movement about its axis of about one-eighth of a turn. By this movement the tooth a^3 on the axis of the handle is brought to bear upon the projection a^2 of the main-spring, which is thus partly compressed, and the compression is completed by the retreat of the striker P^3 , brought about by the two sides of the recess t^4 , which bear upon the enlarged part of the striker, beveled off in front, as shown in Figs. 17 and 18. The striker then moves back a distance of about eight millimeters, when the mainspring is compressed and the nose t^5 of the sear engages with the notch t^6 in the heel P^4 of the striker. By the same movement the two lateral projections b^2 at the two ends of the axis or body of the working-handle E have been made to quit their seat in the mortises b within the breech-box, and the axis or body by pressing against the two tenons N, placed in front of it, has compelled the bolt P to move back about three millimeters, taking with it the extractor and forcing out the cartridge-case the same distance. The bolt is then free, and when drawn back by the hand can follow in its rearward movement the grooves within the breech-box which guide it. The extractor M', which it takes with it, draws out the empty cartridge-case until the point l' on the extractor strikes against the transverse bar M within the breech-box at the point l , and then a violent movement is produced, which effects the ejection of the empty cartridge-case out of the opening B of the breech-box and throws it over toward the muzzle of the gun. The gun is then open and the percussion mechanism is ready to again operate. The bolt P in its retreat leaves the opening in the magazine free. The carrying-lever 9, under the influence of its spring, immediately acts upon the four cartridges remaining in the magazine, and the upper cartridge presents its base before the face of the bolt. On pushing this forward the front of the hook of the extractor bears against the base of the cartridge and thrusts it into the chamber. As soon as the cartridge is in place the hook of the extractor passes under the flange, and the face of the bolt is then in contact with the base of the cartridge. The arm is now again loaded, and it is only necessary to press the finger upon the trigger to fire another shot. The same rectilinear movements to and fro are repeated until the five cartridges in the

box are expended, and then this is allowed to fall out of the magazine by its own weight, passing through the opening at the bottom of the magazine. A new box with five cartridges is then inserted into the opening of the breech-box and the firing is continued in the same manner.

When it is desired to take apart the mechanism, the breech-stop, Fig. 38, is put at its dead-point and the bolt P is drawn out of the breech-box. To take the bolt apart, it is necessary that the mainspring should be uncom-pressed and that the striker P^3 should have made its forward movement. The safety-bolt, Fig. 26, is then taken out by turning it a quarter-round on its trunnions, then the sear is removed, and successively the spring, the striker, the working-handle, and the ex-tractor.

To put together the parts of the bolt mechanism, the parts are assembled in the reverse order.

To take the repeating apparatus apart, it is necessary first to remove the screw e from the end of the breech-box, then to take out the magazine, taking hold of it by the trigger-guard. It is then necessary to take off the left side of the magazine, which exposes the interior of the box, from which the elevating-lever 9 and its spring 13 are then taken. The stop-lever is then taken out, and finally the trigger.

In putting together the parts of the repeating apparatus they are taken in the reverse order.

What I claim is—

1. In combination, the breech-box, the sliding bolt, the striker carried thereby, and a safety-bolt for locking the striker in retracted position, said safety-bolt being carried by the sliding bolt in proximity to the striker, and being adapted to engage tenons on the striker, substantially as described.

2. In combination, the breech-box, the sliding bolt, the sliding striker having tenons t , a safety-bolt pivoted to the bolt and having hooks t' , adapted to engage with the tenons t , said safety-bolt having also a projection b^3 , arranged to engage a recess in the bottom of the breech-box for securing the striker, substantially as described.

3. In combination, the sliding bolt having a shoulder f , the stop I, pivoted to the breech-box having a front and rear shoulder adapted to be thrown into line with the shoulder f , means for operating said pivoted stop, whereby the forward shoulder may be brought into action to limit the movement of the bolt for intermittent firing, or the arm may be adapted for magazine-firing by bringing the rear shoulder into action, substantially as described.

4. In combination, the breech-box having tenons N N, the bolt carrying the extractor, and the movable handle E, carried by the bolt, said handle having lateral projections to engage with the tenons N N, for starting

back the bolt and partially withdrawing the cartridge.

5. In combination, the breech-box having mortises *b b*, the bolt carrying the striker, and 5 the movable handle *E*, carried by the bolt, said handle having projections adapted to the mortises *b b* in the breech-box for locking the bolt in position.

6. In combination, the breech-box, the bolt, 10 the striker carried thereby, the movable handle *E*, carried by the bolt, said striker having shoulders, and said handle also having shoulders adapted to engage therewith for retracting the striker, substantially as described.

7. In combination, the breech-box, the sliding bolt with the striker, the trigger, sear, and mainspring, and the movable handle *E*, having a tooth for engaging with and 20 compressing the mainspring, substantially as described.

8. In combination, the breech-box having mortises, the bolt, the striker having shoulders, the mainspring, and the pivoted handle, the axis of which has shoulders for en- 25

gaging the mortises in the breech-box, shoulders for engaging the shoulders on the striker, and a tooth for engaging the mainspring, substantially as described.

9. In combination, the breech-box, the bolt, 30 the striker, the sear engaging therewith, the mainspring, and a link-piece *P⁵*, pivoted to the striker and engaging with the mainspring, and means for moving the striker within the bolt, substantially as described. 35

10. In combination with the breech-box, a sliding bolt having a shoulder, a magazine, and an adjustable stop to engage said shoulder to regulate the movement of the bolt in opening the breech, whereby the arm may be 40 adapted for intermittent or magazine firing, substantially as described.

In testimony whereof I have hereunto set my hand in the presence of two subscribing witnesses.

CASPER ENGH.

Witnesses:

N. LIBISULLY,
L. MORISON.
